ELECTRICAL IGNITION APPARATUS FOR INTERNAL-COMBUSTION ENGINES.

1,091,906.

Specification of Letters Patent. Patented Mar. 31, 1914.

Application filed August 27, 1912. Serial No. 717,252.

To all whom it may concern:

Be it known that I, ARNOLD ZÄHRINGER, engineer, a subject of the Emperor of Germany, residing at and whose post-office address is Hoppenlaustrasse 11-13, Stuttgart, Germany, have invented certain new and useful Improvements in Electrical Ignition Apparatus for Internal-Combustion Engines; and I do hereby declare the following to be a full, clear, and exact description of the invention, such as will enable others skilled in the art to which it appertains to make and use the same.

The present invention relates to apparatus for automatically adjusting the period of ignition in internal combustion engines, and more particularly to centrifugally operated mechanism arranged to adjust the period of actuation of the mechanical interrupter, and the distributor if desired, relatively to the stroke of the engine in accordance with the speed thereof, without shifting the angular relation between the ignition current generator and the engine.

So far as I am aware, all devices of this kind heretofore disclosed are arranged to angularly displace the armature of the ignition current generator to automatically alter the period of ignition relatively to the stroke of the engine. In such arrangements, the comparatively large mass of the armature is angularly displaced, although the torque to which this mass is subjected is variable throughout each cycle, suddenly reaching a comparatively large value at each period of ignition. Moreover, the rotatable element of the mechanical interrupter and the distributor are usually coupled to the generator so that these parts also are angularly displaced by the same mechanism. In all these cases, the angularly shifting mechanism is necessarily of comparatively large size and, therefore, has the attendant disadvantages, among other things, of increased cost, larger space, and greater weight.

In accordance with my invention, the generator is positively coupled to the engine, while the period of ignition is automatically adjusted to accord with the speed by a centrifugally operated mechanism which angularly displaces the interrupter alone, or the interrupter and the distributor. In this way, the mass to be shifted is comparatively small, and is subjected to a compara-

tively uniform torque throughout, so that the shifting mechanism may be of considerably smaller size than was heretofore possible.

It is immaterial to the broad idea embodied in this invention whether the distributor, if such is used, be driven separately from the engine, or directly from the generator, or from the mechanical interrupter. It is also immaterial whether the rotatable element of the interrupter, comprising either the co-operative contacts or the deflecting cams, be angularly displaced relatively to the stroke of the engine, or whether the normally stationary part be shifted to angularly displace the period of actuation of the co-operative terminals to alter the period of ignition relatively to the stroke of the engine in accordance with the speed.

In the accompanying drawings, illustrating the preferred embodiment of my engine, Figure 1 is an enlarged side view, partly in section and partly broken away, showing the ignition current generator, a mechanical interrupter driven from the generator through a centrifugal coupling, and a distributor driven from the mechanical interrupter; and Fig. 2 is a front view, partly broken away, of the centrifugal coupling of Fig. 1.

The ignition current generator is shown as a magneto having a rotatable armature winding A and stationary field magnets B. The armature is positively coupled to an internal combustion engine, so as to be driven in invariable relation with the engine from the engine shaft.

The centrifugally operated mechanism comprises two arms c pivoted at e, to a member b which is fastened on the shaft a of the magneto armature. These pivoted arms swing outwardly in response to centrifugal action against the stress of connecting springs d, d, the amount of their swinging movements being dependent upon the speed of rotation of the shaft a and consequently upon the speed of the engine. Each arm c is provided with a roller f arranged in a curved slot g of the disk h. The disk h is fastened to the rotatable element k of an ordinary mechanical interrupter, and to the gear i which drives the gear l, thereby rotating the interrupter element k carrying the co-operative contacts and also the brush m of the distributor n.

The deflecting cam *o* of the mechanical interrupter is fixed in position and is adapted to periodically separate the coöperative contacts to interrupt the circuit of the armature winding *A*. In this arrangement, the 5 rotatable elements of the mechanical interrupter, comprising the interrupter contacts, are angularly advanced relatively to the shaft *a* and therefore to the stroke of the engine as the speed increases, the displacing force being dependent upon the sum of the centrifugal forces acting on the arms *c*. During this operation, however, the angular relation between the armature *A* and the 10 stroke of the engine is not changed, and, therefore, the ignition current generator should be capable of producing suitable ignition currents throughout the adjustable range of ignition desired. When the speed 15 of the engine decreases, the arms *c* are swung inwardly by the springs *d* and retard the period of ignition relatively to the stroke of the engine.

Having thus described my invention, what 20 I claim is:

1. In combination with an internal combustion engine, an ignition current generator positively coupled thereto, a mechanical interrupter comprising a rotatable element and a normally stationary element 25 wherein the rotatable element is driven from the engine to periodically alter the circuit of the winding of the generator to produce ignition currents therein, and centrifugally operated mechanism interposed between the rotatable element of the interrupter and its driving means to automatically change their angular relation to vary the period of ignition 30 relatively to the stroke of the engine in accordance with the speed; substantially as described.

2. In combination with an internal combustion engine, an ignition current generator positively coupled thereto, a mechanical interrupter comprising a normally-fixed deflecting cam and a rotatable element 45 driven from the engine and adapted to co-operate with the cam to periodically alter the circuit of the winding of the generator to produce ignition currents therein, and centrifugally operated mechanism interposed between the rotatable interrupter element and its driving means to automatically 50 change their angular relation to vary the period of ignition relatively to the stroke of the engine in accordance with the speed; substantially as described.

3. In combination with a multiple cylinder internal combustion engine, an ignition 55 current generator positively coupled thereto, a mechanical interrupter driven from the engine to periodically alter the circuit of the winding of the generator to produce ignition currents therein, a distributor driven from the engine for distributing the igni-

tion currents to the cylinders in proper order, and centrifugally operated mechanism interposed between the distributor and its driving means to automatically change their angular relation in accordance with the speed of the engine; substantially as described. 70

4. In combination with a multiple cylinder internal combustion engine, an ignition current generator positively coupled thereto, a mechanical interrupter driven from the engine to periodically alter the circuit of the winding of the generator to produce ignition currents therein, a distributor positively 75 coupled to the interrupter for distributing the ignition currents to the cylinders of the engine in proper order, and centrifugally operated mechanism interposed between the interrupter and its driving means to automatically change their angular relation to vary the period of ignition 80 relatively to the stroke of the engine in accordance with the speed, and also to simultaneously change the angular position of the distributor in accordance with the position of the interrupter; substantially as described. 85

5. In combination with an internal combustion engine, an ignition current generator positively coupled thereto, a mechanical interrupter comprising a rotatable part and a stationary part adapted to coöperate therewith to periodically alter the circuit of the winding of the generator to produce ignition currents therein, a coupling member fastened to the generator to rotate therewith, a coupling member fastened to the interrupter to rotate therewith, and centrifugally operated mechanism interposed between said coupling members to automatically 95 change their angular relation to vary the period of ignition relatively to the stroke of the engine in accordance with the speed; substantially as described. 100

6. In combination with a multiple cylinder internal combustion engine, an ignition current generator positively coupled thereto, a mechanical interrupter comprising a rotatable part and a stationary part adapted to coöperate therewith to periodically alter the circuit of the winding of the generator to produce ignition currents therein, a coupling member fastened to the generator to rotate therewith, a coupling member fastened to the rotatable part of the interrupter, a distributor positively coupled to the rotatable part of the interrupter for distributing the ignition currents to the cylinders of the engine in proper order, and centrifugally operated mechanism interposed between the coupling members to automatically 115 change their angular relation during the period of ignition in accordance with the speed of the engine, and also to simultaneously change the angular position of 120

125

the distributor in accordance with the position of the interrupter; substantially as described.

7. In combination with an internal combustion engine, an ignition current generator positively coupled thereto, a mechanical interrupter comprising a rotatable part and a stationary part adapted to coöperate therewith to periodically alter the circuit 10 of the winding of the generator to produce ignition currents therein, a coupling member fastened to the generator to rotate therewith, a coupling member fastened to the rotatable part of the interrupter, a pair of 15 pivoted arms connected together by spring

mechanism and connected to the coupling members in such manner as to angularly advance the interrupter in the direction of rotation with a force determined by the sum of the centrifugal forces acting on the 20 two arms in order to advance the period of ignition relatively to the stroke of the engine as the speed increases; substantially as described.

In testimony whereof I affix my signature, in presence of two witnesses.

ARNOLD ZÄHRINGER.
